TAMPERPROOF SEAL FOR CAPS

Filed Oct. 8, 1925

Inventor
George A. Williams
By Hull, Brock & West
Atty's.

UNITED STATES PATENT OFFICE.

GEORGE A. WILLIAMS, OF DECATUR, ILLINOIS, ASSIGNOR TO WILLIAMS SEALING CORPORATION, OF DECATUR, ILLINOIS, A CORPORATION OF ILLINOIS.

TAMPERPROOF SEAL FOR CAPS.

Application filed October 8, 1925. Serial No. 61,179.

This invention relates generally to a tamper proof seal for nozzles and the object of the invention is to provide a novel seal for use in connection with filling can nozzles or with bottle closures which will prevent any withdrawal of the contents of the can or bottle without either breaking the seal or mutilating the closure. Caps of this character embody in their structure a lever for locking 10 the cap upon the nozzle, this lever resting substantially parallel with the nozzle when in its locked position.

The object of this invention is to provide an exceedingly simple but at the same time 15 efficient construction of lock or seal for the lever, which must be severed or broken in order to initially remove the cap from the nozzle. By means of this lock or seal the 20 genuineness of the contents of the receptacle can be assured. Inasmuch as these caps are generally applied to the nozzles by machinery in rapid succession the seal must be of such construction that it can be rapidly applied 25 to the nozzles.

Another object of the invention is to provide a seal which is well adapted for all 30 types of removable closures whether they be machine affixed closures or hand applied closures.

With these objects in view the invention consists in the novel features of construction as will be hereinafter more fully described and set forth in the appended claims.

In the drawings forming a part of this 35 specification Fig. 1 is a perspective view of a filling can nozzle with my seal attached thereto; and Fig. 2 is a perspective view of the seal removed from the nozzle.

In Fig. 1 the numeral 1 designates a conventional filling can having the usual discharge nozzle 2 and a sealing closure 3 adapted to be locked in place by a cam lever 4. This form of closure is well known in the art and needs no explanation.

Manufacturers of standard commodities do not wish their containers to be tampered with or refilled with an inferior product and sold as the original package. In order to prevent tampering with or unauthorized removal of 45 the contents of the container I have provided a seal 5 which surrounds the nozzle 2 and cam lever 4 as clearly shown in Fig. 1. This seal or band 5 is a cellulose product and when wet or green is large enough to be slipped

over the nozzle and cap. This band or seal 55 is of such width that when resting upon the top of the can it will extend up over and embrace the lower end of the locking lever 4 of the cap and it will be understood that the band after it has dried or cured and contracted 60 will be of such size as to snugly embrace the nozzle or neck and lever and when so contracted cannot be slipped over the cap and will prevent its removal over the top of the cap. The width of the band also lends 65 itself to the printing of any cautionary legend or advertising matter, if so desirable. The bands may be slipped over the nozzle while wet and allowed to dry thereon and when dry they contract and harden or set and firmly hold the lever 4 against the nozzle. It will now be clear that it will be impossible to remove the cap without damaging or breaking the seal. Suitable indicia or advertising matter may be placed on the seal, for example: "Contents guaranteed if seal is unbroken," or words to that effect.

The operation of sealing is not delayed until the bands are shrunk. Cans or bottles can be packed immediately after the bands 80 are applied. In case the seal is applied to a bottle the bottles are usually labeled before the bands are applied. Cans as a rule are lithographed and if they are to be labeled the labels are applied before the seal is 85 applied.

It will now be clear that I have provided a seal which will accomplish the objects of the invention as hereinbefore stated and that I have provided an effectual means for preventing unauthorized use of original containers 90 to the detriment of the original vendor.

It is to be understood that I do not limit myself to a cellulose seal as any product having similar qualities may be used, I 95 further wish it to be understood that my seal is applicable to all forms of containers in which it may be desirable to seal the cap or closure on the container.

Having thus described my invention, what I claim is:—

1. A closure seal comprising an endless band adapted to be placed about the neck or nozzle of a container and the lever of a cap applied thereto, said band being placed 105 thereon in a given uncured or undried condition and adapted to contract upon curing or drying to grip said lever and nozzle or

neck of container and prevent movement of said lever without breaking contracted sealing band.

2. A container neck or nozzle having a cap applied thereto, said cap having a locking lever resting adjacent said neck or nozzle and a sealing band around said neck or nozzle and lever of cap, said band gripping said parts tightly upon contraction upon drying or 10. curing for the purpose specified.

3. The combination with a nozzle and cap applied thereto, said cap having a lever adapted to rest in parallel relation with the nozzle when the cap is fastened upon said 15. nozzle, of a band applied in uncured or un-

dried condition to surround said nozzle and lever and adapted to contract upon curing or drying to securely hold said lever.

4. The combination with a container of a cap applied thereto, said cap having a lever adapted to rest in parallel relation with the side of the container when the cap is locked thereon, and a continuous band applied in moist and extended condition to surround said container and lever and adapted to contract 20 upon drying to securely hold said lever. 25

In testimony whereof, I hereunto affix my signature.

GEORGE A. WILLIAMS.
